UNEQUAL STROKE SPEED EXPANSIBLE
CHAMBER MOTOR WITH INDEPEND-
ENT ADMISSION AND EXHAUSTLeroy J. Carey, Cleveland, Ohio, assignor to The
Marquette Metal Products Company, Cleveland,
Ohio, a corporation of Ohio

Application January 6, 1945, Serial No. 571,596

3 Claims. (Cl. 121—124)

1

This invention relates to fluid operated motors and more particularly to a fluid operated motor in which the average speed of a reciprocating power take-off shaft or shafts differs for the respective opposite directions of its travel during a complete working cycle.

The motor of this invention has a reciprocating piston assembly, is of the general type described and claimed in the copending application of John H. Galley and Leroy J. Carey, Serial No. 548,692, filed August 9, 1944, now Patent No. 2,450,653, and possesses all of the advantages of the motor of said application such as large power output for unit size and weight, high efficiency, ease of manufacture, reliable operation even when supplied with fluid at extremely high pressures, simplicity of stroke adjustment, and ability to function with gas or liquid as the operating medium. In the preferred embodiment shown in the drawings hereof, a power take-off shaft disposed at one end of and forming a part of the reciprocating piston assembly is driven axially to and fro at the same speed as the piston. Obvious modifications which are not shown in the drawings include the use of a pair of power take-off shafts disposed respectively at opposite ends of the piston and the use of a rack and pinion driven valve actuating shaft as a power take-off shaft in the manner disclosed in the foregoing application. When provided with oppositely extending power take-off shafts, the motor is useable, for example, to effect relative fast and slow motion of machine tool control elements.

Prior fluid motors of the type herein shown and having reciprocating pistons or the like are unsuitable for many applications since the piston speed and consequently the speed of the reciprocating power take-off shaft or shafts are the same for the respective opposite directions of travel. For example, it is desirable to drive, by means of a fluid motor, a scraper or ductor (doctor) blade used for cleaning the rolls of a steel strip rolling mill alternately back and forth axially of the roll. When the speed of the blade is the same for both directions of travel, however, the foreign substances removed from the roll by the blade merely rest on the upper surface of the blade, move back and forth therewith, and must be removed by means such as a suction or air blast. On the other hand, if the ductor blade is caused to move relatively fast in one direction and relatively slow in the other direction, the removed foreign substances remain stationary with respect to the blade during the fast move-

ment, travel with the blade during the slow movement, and consequently are translated axially of the roll until they reach one end of the roll and fall from the blade as into a suitable waste receptacle.

The motor of the present invention is admirably suited for driving a ductor blade as above described both because of the arrangement of its reciprocatable power take-off shaft and because the speed of the shaft is relatively fast when moving in one direction and relatively slow when moving in the opposite direction. This desirable speed relationship is obtained by causing the effective area of a restricted portion or portions of the fluid passages leading to a piston chamber at one end of the piston to differ from the effective area of a restricted portion or portions of the fluid passages leading to a piston chamber at the opposite end of the piston. The effective area of the restricted portion of the exhaust passage which is operative during slow movement of the piston may be so related to the effective area of the restricted portion of the inlet passage which is also operative during said slow movement so that the restricted portions in the inlet and exhaust passages cooperate to stabilize the motor operation.

An object of this invention is to provide an improved fluid motor.

Another object is to provide a fluid motor having a reciprocating power take-off shaft capable of moving at different speeds for the respective opposite directions of its travel during a working cycle.

A further object is to provide an improved valve mechanism for a fluid operated motor.

Still another object is to provide a fluid operated motor having alternately operative inlet valve ports of different sizes, respectively.

Another object is to provide a fluid operated motor having alternately operative inlet passages containing restricted portions of different sizes, respectively.

A more specific object is to provide a fluid operated motor having valve ports for admitting operating fluid for driving a power take-off shaft in opposite directions, respectively, the valve ports operative during movement of said shaft in one direction being different in size from those operative during movement of said shaft in the opposite direction.

Other objects include the provision of an improved packing means around an axially reciprocating power take-off shaft of a fluid operated motor, the provision of a novel piston and axially

2

reciprocating power take-off assembly, and the provision of safety fluid passage means extending through the power take-off shaft.

A further object is to provide a fluid motor in which the effective area of outlet and inlet passages are cooperatively related to cause stable operation at relatively slow speeds.

Other objects and advantages of this invention will become apparent from the following description wherein reference is made to the drawings, in which

Fig. 1 is a sectional view of the motor taken as indicated at 1—1 in Fig. 2;

Fig. 2 and Fig. 3 are sectional views taken generally as indicated at 2—2 of Figs. 1 and 4, and 3—3 of Fig. 1, respectively; and

Fig. 4 is a sectional view taken generally as indicated at 4—4 of Fig. 2.

Referring to the drawings, a housing for the motor comprising an irregularly shaped body member 10 which may be a cored casting or die casting of any suitable metal or alloy or, for further example, a plastic molding, suitably formed and/or bored to accommodate the working parts and to provide a minimum of wall thickness. The working parts of the motor comprise generally a reciprocatable piston assembly 11 (Fig. 3) including a power take-off shaft 12, a fluid flow control or valve mechanism (Fig. 2 principally) and a valve actuating assembly (Figs. 2, 3 and 4) which is driven by the piston assembly for actuating the valve mechanism and which includes a snap-action or toggle mechanism 14 (Figs. 2 and 4).

Considering particularly Fig. 3, the power take-off shaft 12 is slidably received for reciprocation within a central aperture 15 in an internally recessed plug 16 threaded into a counterbore formed at one end of a cylinder bore 18 (Figs. 1 and 4 also) extending through the body 10. An exteriorly threaded tubular extension 20 co-axially with the aperture 15 and extending outwardly from an outer face surface 21 of the plug 16 has its interior wall surface spaced from the aperture 15 and the shaft 12 to accommodate a suitable fluid seal. As shown, said seal comprises a plurality of stacked elastic packing rings 22 of concavo-convex section interposed between an outer convex face portion 24 of a metal washer 25 and a concave inner end face 26 of a flanged sleeve or collar 28. The inner face portion of the washer 25 bears against the surface 21 and the collar 28 has its flange received in a shouldered recess formed at the outer end of the extension 20. A centrally apertured gland nut or thimble 29 loosely surrounds the shaft 12 and is threaded on the extension 20 and forces the collar 28 into compressing engagement with the rings 22.

A reduced inner end portion 30 of the shaft 12 is threaded into an end portion of a longitudinal bore 31 in a rack member 32 of the piston assembly 11, a set screw 33 being provided if desired to secure the threaded joint against loosening. The rack member 32 is slidably received for reciprocation within a piston sleeve 34 pressed into the cylinder bore 18 and, intermediate of its ends, is of generally rectangular cross section (Fig. 4) having teeth 35 on its upper surface but having a lower curved surface and completely cylindrical end portions complementary to the inner wall of the piston sleeve which may be of high strength alloy if extremely high pressure fluid is to be used.

A flexible sealing cup 36 is held in an annular shouldered recess at the shaft end of the rack 32 by an integral flange on the inner end of the shaft 12, which flange thereby constitutes a piston head, and a second sealing cup 36 is similarly received in a shouldered recess at the opposite end of the rack member 32 and is held therein by a piston head 39 threaded into an end portion of the bore 31.

member 32 by an integral flange on the inner end of the shaft 12, which flange thereby constitutes a piston head, and a second sealing cup 36 is similarly received in a shouldered recess at the opposite end of the rack member 32 and is held therein by a piston head 39 threaded into an end portion of the bore 31.

A central axial bore 40 extending through the piston head 39 and a central axial bore 41 extending into the inner end portion of the shaft 12 define a pair of valve seats 42 complementary respectively to a pair of ball valves 43 releasably held in seated position thereon by a helical spring 44 interposed between the balls. A plurality of transverse bores 47 in the race member 32 serve as fluid passages for fluid admitted into the bore 31 upon unseating of one or both of the balls 43 in a manner to be described later.

The cylinder bore 18 is sealed at its end opposite the shaft 12 by an internally recessed castellated plug 45 threaded into a counterbored portion of the bore. The plugs 16 and 45 have respective inner chamfered portions bearing against and compressing annular elastic packings 46, respectively, seated on shoulders defined by the bottoms of the respective counterbores. Piston chambers 48 and 49 are thereby formed at opposite ends of the rack member 32. It is readily apparent that, by a mere interchange of parts, the shaft 12 may be operatively disposed at the opposite end of the piston assembly 11 from the end at which shown, or that a second shaft 12 and cooperating sealing assembly may replace the piston head 39 and the plug 45 to form a motor having two oppositely directed power take-off shafts.

Central bosses 50 and 51 in the recesses of the plugs 16 and 45, respectively, serve as stops for the piston assembly 11 when the motor is adjusted for maximum stroke operation. The boss 50, due to the aperture 15, is in the form of a hollow cylinder and has a plurality of radial slots in its face defining ports 52 communicating, when the piston assembly is in the position shown in Fig. 3, with mutually intersecting diametrical bores 53 and 54 in the shaft 12 which intersect the inner end portion of the axial bore 41.

Referring to Fig. 2, a pair of coaxial valve bores 55 in the body 10 parallel to and above the cylinder bore 18 and opening into a recess 56 respectively receive a pair of flanged valve guides in the form of sleeves 58 and 59 constituting a part of the valve assembly. The valve assembly additionally comprises a pair of preferably similar valve plungers 60 and 61 slidably received for reciprocation in the sleeves 58 and 59, respectively. The valve plungers are in a sense free floating although caused to move simultaneously in opposite directions as though interconnected.

Each of the bores 55 has four portions of progressively smaller diameter inwardly of the housing 10 which define three spaced shoulders 64, 65 and 66 in each bore and each of the valve sleeves 58 and 59 has outwardly projecting spaced annular flanges 68 and 69 intermediate of its ends. The outermost portions of the bores 55 are threaded to receive respective castellated plugs 70, reduced inner ends of which are piloted within the respective valve sleeves 58 and 59 to assist in holding the sleeves in coaxial relationship and centered in the respective bore portions which receive the sleeves. Elastic ring packings 71 are compressed between shouldered portions of the plugs 70 and the shoulders 64 of the bores 55, respectively, and similar packings 72 are inter-

posed between inner faces of the plugs 70 and the flanges 68 of the sleeves, respectively. In addition, elastic ring packings 74 are inserted between the flanges 69 of the valve sleeves and the respective bore shoulders 66. The machining dimensions between the plugs 70 and the respective valve sleeves 58 and 59 are such that before metal to metal contact therebetween occurs the packings 72 are squeezed out or extruded against the walls of the respective bores 55 and the packings 74 are made thick enough so that they are compressed a considerable amount at the same time that the packings 72 are compressed. Thus by merely screwing the plugs 70 into position, the sleeves 58 and 59 are properly positioned and the bores 44 sealed against fluid leakage.

An annular chamber 75 defined by a circumferential groove in the left hand plug 70 (Fig. 2) communicates with the interior of the valve sleeve 58 through radial passages 76 and an axial passage 78 in the plug 70. A port 79 of relatively small size and a pair of diametrically opposed ports 80 and 81 of relatively larger size than the port 79 permit fluid to flow between the interior of the sleeve 58 and a chamber 82 defined by the annular space around the sleeve 58 between the flanges 68 and 69. Similarly, an annular chamber 84 defined by a circumferential groove in the right hand plug 70 (Fig. 2) communicates with the interior of the sleeve 59 through radial passages 85 and an axial passage 86 in the plug. A pair of diametrically opposed ports 88 and 89 of relatively small size and a pair of diametrically opposed ports 90 and 91 of relatively large size permit fluid to flow between the interior of the sleeve 59 and a chamber 92 defined by the annular space around the sleeve 59, end walls for which space are formed by the flanges 68 and 69 of the valve sleeve 59. The valve plungers 60 and 61 have respective inner portions 94 and 95, respectively, of reduced diameter adapted to cooperate with a push rod 96 of the valve actuating assembly. The preferred relationship of the sizes of the various ports 79, 80, 81 and 88 to 91 will be more fully explained in subsequent consideration of the operation of the motor.

Referring now to Fig. 4, the valve actuating assembly comprises a rotatably supported shaft 100 disposed above and extending transversely of the rack member 32 within a recess 101 formed in a side face of the body 10 and opening into the cylinder bore 18. The shaft 100 has an intermediate non-circular portion (e. g. squared) mounting a pinion 102 which is in contact mesh with the teeth 35 of the rack member 32 and is supported at its inner end portion by a flanged bushing 104 pressed into an aperture in an internal wall 105 of the body 10 between the recesses 56 and 101. A reduced outer end portion 106 of the shaft 100 is supported by a bearing member 107 held against an annular shoulder 108 of the recess 101 by a plug 109 having spanner sockets 110 and threaded into the outer end portion of the recess. A washer 111 having a relatively large central opening is disposed between the plug 109 and the bearing member 107 and bears against an elastic packing 112 received in a shouldered recess of the bearing member. A seal around the shaft 100 is provided by a cylindrical retainer 113 received in a complementary axial recess in the inner side face of the bearing member 107 and having an annular shouldered recess adjacent the shaft containing an elastic packing 114. End thrust of the shaft 100 is taken by an integral flange portion 115

thereof which bears against the inner side face of the bearing member 107 and the retainer 113 and by engagement of the flange on the bushing 104 with a portion of the inner side face of the pinion 102.

It is obvious that if desired the shaft 100 may be extended beyond the body 10 as in the above described application and serve as a power take-off shaft instead of or in addition to the shaft 12.

10 A longitudinally serrated portion 115 (Figs. 2 and 4) of the shaft 100 and adjacent the inner end thereof extends into the recess 56 and supports in adjusted turned positions an index or drive plate 116 having a central splined (serrated) opening 118 fitting the shaft and suitably mounting in adjustable circumferentially spaced relation a pair of outwardly extending drive pins 119 only one of which is illustrated. Alternate rotary movement of the shaft 100 causes turning of the plate 116 so that the drive pin 119 alternately strikes a toggle arm 121 rotatably supported on a reduced inner end portion of the shaft 100 and freely turnable on said end portion.

15 The toggle or snap action mechanism 15 includes an upwardly extending tongue portion 122 of a cam 124, which latter is pivoted at its upper end to the arm 121 near the longitudinal center of said arm. The edges of the tongue portion 122 and the top of the main body of the cam define angularly disposed cam or shoulder surfaces 124a and 124b on one side of the cam and cam or shoulder surfaces 124c and 124d on the other side. The cam has parallel side edges below the surfaces 124b and 124d and has a lower triangular portion 125.

20 The arm 121 and the cam 124 are normally held in the right hand position shown by solid lines in Fig. 2 (or in a similar left hand position) due to the combined bias of a helical tension spring 126 suitably secured at opposite ends to pins 128 and 129, respectively, and of a similar spring 130 secured at its lower end to a fixed pin 131 received in a socket in the body 10 and at its upper end to the mid-point of a lower leg of a triangular hollow link 132. The link 132 has its upper vertex received adjacent the upper end of the spring 126 in an annular groove formed near the outer end of the pin 128. The pins 128 and 129 are suitably secured to and project rearwardly from the free end of the arm 121 and the lower end of the cam 124, respectively.

25 Referring now to Fig. 4, the valve actuating assembly comprises a rotatably supported shaft 100 disposed above and extending transversely of the rack member 32 within a recess 101 formed in a side face of the body 10 and opening into the cylinder bore 18. The shaft 100 has an intermediate non-circular portion (e. g. squared) mounting a pinion 102 which is in contact mesh with the teeth 35 of the rack member 32 and is supported at its inner end portion by a flanged bushing 104 pressed into an aperture in an internal wall 105 of the body 10 between the recesses 56 and 101. A reduced outer end portion 106 of the shaft 100 is supported by a bearing member 107 held against an annular shoulder 108 of the recess 101 by a plug 109 having spanner sockets 110 and threaded into the outer end portion of the recess. A washer 111 having a relatively large central opening is disposed between the plug 109 and the bearing member 107 and bears against an elastic packing 112 received in a shouldered recess of the bearing member. A seal around the shaft 100 is provided by a cylindrical retainer 113 received in a complementary axial recess in the inner side face of the bearing member 107 and having an annular shouldered recess adjacent the shaft containing an elastic packing 114. End thrust of the shaft 100 is taken by an integral flange portion 115

plugs 70. A horizontal passage 142 intersects the passage 141 and extends to the other side of the motor where it intersects a vertical passage 143. A needle valve 144 having a knurled head 145 is threaded through a side wall 146 of the body 10 and intersects the passage 141 above the point of intersection with the passage 142 and is arranged to be held in adjusted position by a nut 148.

A passage 149 (Figs. 1 and 2) extends from the chamber 82 to an axial groove 150 (Figs. 1 and 3) in the wall which contains the cylinder forming sleeve 34. The groove 150 opens into an outer enlarged portion of the piston chamber 48 defined by the recess in the inner face of plug 16 (Fig. 3). Similarly, a passage 151 (Fig. 2 only) extends from the chamber 92 to an axial groove 152 (Fig. 3) which opens into an outer enlarged portion of the piston chamber 49 defined by the recess in the inner face of the plug 45. The outer end of the passage 149 may be sealed by a plug 154 (Fig. 1), and a similar plug (not shown) seals the outer end of the passage 151.

In event abnormally high pressure exists in the piston chamber 49, the right hand ball 43 (Fig. 3) becomes unseated and fluid flows through the bore 40 into the bore 31 and thence through the transverse bores 47 into a passage 155 (Fig. 4) to a discharge port 156 whereby the internal pressure is relieved. Should an abnormally high pressure condition exist in the piston chamber 48, the left hand ball 43 becomes unseated and fluid flows into the bore 31 through the radial passages 53 and 54 and the axial passage 41 in the shaft 12. It will be noted that even though the piston assembly 11 is in the extreme left hand position shown in Fig. 3, fluid at abnormal pressure can escape from the chamber 48 due to the provision of the radial slots 52 in the inner face surface of the boss 50 which slots communicate with the respective passages 52 and 53. A safety valve means is thus provided which is operative regardless of the position of the piston assembly 11 and which prevents extremely high or abnormal pressure fluid from causing damage to the motor or to the apparatus driven thereby. Discharge fluid received in the recess 56 flows freely from said recess through a short bottom drain passage 158 (Fig. 2) into the passage 155 and thence to the discharge port 156.

In considering the operation of the motor, the moving parts are assumed to be initially in the position in which shown by Figs. 2 and 3.

Operating fluid supplied in any suitable manner to the inlet port 140 flows through the passage 141 past the needle valve 144, into the annular chamber 75 and thence through the passages 76 and 78, the interior of the valve sleeve 58 at the left of the plunger 60, through the single relatively small port 79, the chamber 82, and the body passages 149 and 150 to the piston chamber 48. Concurrently, fluid enters the passages 142 and 143 and the passages 85 and 86 and exerts a static pressure against the right hand end face of the plunger 61 which is held in the position shown by the push rod 96 and the toggle mechanism 14.

Assuming first that the needle valve 144 is either not used or is adjusted to a position whereby its restrictive effect to fluid flow is less than that afforded by the port 79, fluid flows relatively slowly through the port 79 so that fluid enters the chamber 48 at a relatively slow rate to force the piston assembly 11 to the right at a relatively slow speed. As the piston assembly 11 moves to

reduce the volume of the chamber 49, fluid therein is forced through passages 152 and 151 into the annular groove 92 and thence through the passages 88 and 89 into the space between the push rod 96 and the interior wall surface of the sleeve 59 from where it flows freely into the chamber 56. It has been determined experimentally that steady and uniform slow motion of the piston assembly 11 is obtained if the area of each of the ports 88 and 89 is made approximately equal to the area of the port 79. If the size of the ports 88 and 89 is increased beyond a certain limit, for example equal to the size of the ports 80 and 81, unstable and erratic operation occurs and the desired slow speed is not obtained.

As the piston assembly 11 moves to the right, the rack teeth 35 drive the pinion 102 counterclockwise (Fig. 3) to effect rotary movement of the shaft 100. Rotation of the shaft 100 counterclockwise rotates the index or drive plate 116 counterclockwise as shown in Fig. 2 to cause one of the drive pins 119 to rotate the toggle arm 121 counterclockwise from the position shown by the solid lines in Fig. 2 against the combined bias of the springs 126 and 130 to the position shown by the broken lines in the same figure. It will be noted that said broken line position is the dead center position of the spring 126, but that said position is slightly beyond the dead center position of the spring 130. The cam 124 is raised and shifted to the left as indicated by said broken lines during this portion of the movement of the arm 121, but the cam surface 124a is not yet in contact with the end of the pointed shoulder 134 of the push rod 96. However, the corner at the outer end of the cam surface 124d is now in sliding contact with the lower beveled surface of the pointed shoulder 135 of the push rod 96 so that the latter still holds the valve plunger 61 in the initial position shown. Although the pressures on the two valve plungers tending to force the plungers toward the push rod 96 are balanced, it should be observed that a slight difference in working clearance between the valve plungers and their guide bores or foreign matter in the operating fluid would cause one of the plungers to move more freely in its guide bore than the other plunger does, hence the importance of holding the push rod in position while the toggle mechanism is moving from either extreme position to the dead center position at each half cycle of valve operation or during each stroke of the snap action mechanism.

Shortly after the arm 121 has passed through the dead center position of the spring 126, the cam surface 124a strikes the end of the beveled portion 134 with a hammer blow, which moves the push rod 96 to the left. It is to be noted that by the time the cam surface 124a and the shoulder 134 are in contact, the cam surface 124d has parted from the shoulder 135 to permit movement of the push rod to the left. The toggle arm 121 and associated parts continue to move counterclockwise due to the combined bias of the springs 126 and 130 until an extreme left hand position is reached corresponding to the initial position of the toggle parts shown at the right in Fig. 2 but not illustrated. Since the springs 124 and 130 do not have the same dead center position, there is no possibility of hesitation or stalling during travel of the arm 121.

Movement of the push rod 96 to the left drives the valve plunger 60 to the left to open the ports 80 and 81 and to cut off, at the port 79 the fluid

pressure supply from the inlet port 140 to the piston chamber 48. Concurrently, the valve plunger 61 moves to the left, due to the direct connection of the passage 86 with the inlet port 140, and closes the ports 88 and 89, and opens the ports 90 and 91 so that fluid flows from the passage 86 into the chamber 92 and through the passages 151 (Fig. 2) and 152 (Fig. 3) into the piston chamber 49.

High pressure fluid thus introduced into the chamber 49 returns the piston assembly 11 to its initial position at a higher rate of speed than that obtained during movement of the piston assembly to the right away from its initial position. During such return movement, the rack teeth 35 drive the shaft 100 clockwise (Fig. 2) and consequently the other of the spaced drive pins 119 engages the toggle arm 121 and returns the latter through a dead center position (not shown) with a snap action as before. The cam surface 124b holds the push rod 96 in its left hand position until just before the cam surface 124c strikes with a hammer blow against the shoulder 135, which operation occurs shortly after the dead center position of the spring 126 is passed. The valve plunger 61 is thus forced to its initial position by the push rod 96, and fluid pressure in the passage 78 simultaneously returns the left hand valve plunger 60 to its initial position.

During movement of the piston assembly 11 to the left toward the position shown, fluid in the piston chamber 48 is discharged through the passages 150 and 149, the chamber 82, the ports 80 and 81, the segmental spaces between the push rod 96 and the guide 59, the toggle-containing recess 56, and the discharge passages 158 and 155 to the outlet or discharge port 156 of the body 10. The ports 80 and 81 may be and preferably are each of the same size as each of the ports 90 and 91.

As more fully described in the above mentioned copending application, means may be provided for adjustably mounting the pins 119 on the drive plate 116, so as to permit regulation of the length of the stroke of the piston assembly 11 and consequently of the shaft 12.

Selection of a valve sleeve 58 having a port 79 of given size predetermines the maximum possible speed of the shaft 12 during the slow speed portion of its cycle. Speeds below this maximum slow speed may be obtained by adjusting the needle valve 144 so that the restrictive effect provided thereby in the passage 141 is greater than the restrictive effect provided by the port 79, it being apparent that the needle valve 144 is of no effect which is less than that provided by the port 79.

I claim:

1. A fluid operated motor comprising a cylinder, a piston reciprocatable within said cylinder, piston chambers in said cylinder at opposite ends of said piston respectively, supply passages for conducting fluid under pressure into said chambers

alternately to reciprocate said piston, flow control means in said passages respectively having different operative effects on the flow of fluid thereby to cause the fluid to flow more freely into one chamber than into the other chamber, one of said flow control means comprising a fixed relatively restricted orifice and an adjustable valve in series therewith relative to the flow of fluid in one only of the supply passages, and exhaust means for conducting fluid alternately from said chambers independently of said supply passages.

2. A fluid operated motor comprising a cylinder, a piston reciprocatable within said cylinder, piston chambers in said cylinder at opposite ends of said piston respectively, valve means for admitting fluid under pressure into said chambers alternately to reciprocate said piston, said means including orifice means for causing said fluid to enter into one of said chambers at a faster rate than into the other of said chambers, valve means for conducting fluid from said chambers alternately as said piston reciprocates, said last named means including orifice means for causing the rate of flow of fluid from said one of said chambers to be slower than from said other of said chambers, and a single means operatively connecting the piston to both valve means to operate them alternately.

3. In a fluid operated motor having a cylinder, a double ended piston mounted for reciprocation in said cylinder, a first valve mechanism for regulating the flow of fluid to and from said cylinder at one end of said piston, a second valve mechanism for regulating the flow of fluid to and from said cylinder at the opposite end of said piston, mechanism operated by said piston to control said valve alternately, thereby to effect reciprocation of said piston, said first valve mechanism being arranged to cause fluid to be admitted to said cylinder at a slower rate than said second valve mechanism, and said first valve mechanism being arranged to permit fluid to be exhausted from said cylinder at a faster rate than said second valve mechanism.

LEROY J. CAREY.
